File No. 1753

Carl Müller, of New York, N. Y.

accord to

John Matthews, of same place.

Letters Patent No. 1753. Dated April 28, 1863.

The Schedule referred to in these Letters Patent and making part of the same.

Dec. 1753

To all whom it may concern:

Be it known that I, Carl Müller, of the City, County, and State of New York, have invented or produced a new and original design for a Draught Stand for Soda Water, &c; and I do hereby declare that the following is a full and exact description thereof, reference being made to the annexed drawing, forming a part of this specification, in which.

Figure 1. is a side view or elevation.

Figure 2. is of a part in detail; and similar letters indicate similar parts in both the figures.

At a. is a cylindrical base upon which is a torus b. ornamented with scales and bands, as shown; on this is a narrow fillet c. above which the size is diminished by a moulding d. having the form of an inverted "cima-recta" ornamented as shown. From this rises a cylindrical shaft, the lower part of which is ornamented, as shown at e, with alternate scroll and leaf work. Above this is a broad band f. passing around the cylinder about midway of its height, and having on it antique figures of living objects in relief, being in number and character as shown in Fig. 2. which is a representation of the band as laid flat. The portion of the cylinder at g. is ornamented by a figure similar generally to that at e. but somewhat smaller in its proportions, as shown. There is then a small fillet h. and above this a "cima-reversa" i. surrounded by a cap k. covered with depending leaves at l. as shown, and terminating in a representation of a cone of the Norway Spruce pine, as at m.

On opposite sides of the cylindrical shaft, and near the top, project horns n. turned inward; from each of these depends a representation of a Fuschia o. the stem being entwined around the horn and the pistilla of the flower forming the tube through which the soda-water is discharged, as shown.
